UNITED STATES PATENT OFFICE.

BENJAMIN B. SCULLY, OF LYNN, MASSACHUSETTS.

NECKTIE-SUPPORTER.

SPECIFICATION forming part of Letters Patent No. 330,743, dated November 17, 1885.

Application filed April 15, 1885. Serial No. 162,270. (No model.)

To all whom it may concern:

Be it known that I, BENJAMIN B. SCULLY, of Lynn, in the county of Essex and State of Massachusetts, have invented a new and useful Improvement in Necktie-Supporters, which will, in connection with the accompanying drawings, be hereinafter fully described, and specifically defined in the appended claims.

This invention is an improvement in that 10 class or kind of necktie-supporters for which Letters Patent of the United States No. 293,792 were issued to me on the 19th day of February, A. D. 1885, and it is shown in connection with the loop secured to me in that patent; but it is not confined thereto, as it is applicable to many varieties of loops by which 15 the supporter is secured in position.

In the accompanying drawings, Figure 1 is a rear elevation of the central portion of a 20 necktie-supporter embodying my invention. Fig. 2 is a front elevation of the same; and Fig. 3 is a transverse section through Figs. 1 and 2, said several figures being enlarged, the better to show the invention.

25 In said views, A represents the body of the supporter, which may be formed of any suitable material, and of any desired form of outline. The securing-loop is shown as formed with the elastic arms b, by which it is secured 30 in position. The central portion, c, as also the ends d of the wire which composes the

loop, are passed through an eyelet, f, which is oval in outline, and which protects body A and secures the loop in position, while the bight of the central part, c, is secured in position by eyelet e, as shown, and as was fully described and shown in my said former patent. The ends d are firmly clinched upon body A.

I do not claim the method of passing center c and ends d through the body A and then securing the loop in position by the eyelet e, my invention consisting in the combination of an oval eyelet, f, with the other devices, as defined in the following claims. 45

I claim as my invention—

1. In a necktie-supporter, the combination, with body A and the securing-loop, of oval eyelet f, secured in said body, to serve as the opening in which the securing-loop rests, 50 substantially as specified.

2. In a necktie-supporter, the combination, with body A and the securing-loop, of oval eyelet f, secured in said body, to serve as the opening in which the loop is inserted, and eyelet e, arranged to secure the central portion of the loop to the body, substantially as specified. 55

BENJAMIN B. SCULLY.
